UNITED STATES PATENT OFFICE.

SAMUEL P. EDMONDS, OF CATONSVILLE, MARYLAND.

LIFE-SAVING APPLIANCE.

1,110,614.

Specification of Letters Patent. Patented Sept. 15, 1914.

Application filed November 20, 1912. Serial No. 732,473.

To all whom it may concern:

Be it known that I, SAMUEL P. EDMONDS, a citizen of the United States, residing at Catonsville, in the county of Baltimore and State of Maryland, have invented certain new and useful Improvements in Life-Saving Appliances, of which the following is a specification.

My invention relates to life-saving apparatus which may serve as mattresses for use not only in bunks and beds on shipboard but also in houses, and hotels along water-ways where floods and overflows may take place suddenly and endanger the lives of those living in the vicinity.

The main object of my invention is to provide a mattress which, when used in the ordinary manner upon a bed, retains its resiliency but which is at all times available for immediate use as a float and will sustain a number of persons for a period of days. In my present invention I provide an envelop surrounding the mattress which is water-proof and may be substantially airtight so that it may constitute a pneumatic casing and thus add to the buoyancy of the mattress, which is itself formed of buoyant material. I preferably inclose the water-proof envelop with an outer casing or ticking to form a suitable cover and to act as a protecting sheath for the inner casing.

The several objects of my invention will appear from the following description in connection with the accompanying drawings, in which—

Figure 1 is a perspective view of a mattress embodying my invention and showing its use as a life-saving float; Fig. 2, is a perspective view of the same with portions of the inner and outer covers ripped open and laid open to expose the mattress and metal frame; Fig. 3, is a bottom plan view of my life-preserving mattress with one corner of the outer cover turned back and other portions of the outer and inner covers cut away to expose the mattress; Fig. 4, is a detail showing one end of the mattress and frame in section, taken on the line 4—4 of Fig. 3; Fig. 5, is a detail showing in section a water-proof fabric which I may employ for the inner pneumatic cover; Fig. 6, is a detail of one corner of the outer cover showing the manner of inclosing or pocketing the metal frame; and Fig. 7, is a detail showing the manner of forming the water-proof joints.

It is absolutely essential that the float should be rigid and not sag in the center or bend under the great torsional stresses to which it may be subjected by the violence of the waves. It is therefore necessary to provide a rigid marginal stiffening frame. However, when used as a mattress upon bunk or bed, it is desirable to retain all of the available resiliency of the mattress. For both reasons I place the frame at the bottom of the mattress and secure the bottom of the outer cover thereto in a manner to maintain it taut and to prevent any sagging.

The mattress 1 may be constructed of felt or other resilient material and be provided with the usual ticking. Such mattresses possess sufficient buoyancy to be used as floats, but I prefer to employ a resilient filler such as water-proof silk floss, which is in itself a substantially water-resisting material, to prevent being water-soaked in case the cover becomes ruptured or torn.

For the purpose of making the mattress water-proof and also to add to the buoyancy thereof, I incase the mattress in a water-proof casing 4, which constitutes in effect a pneumatic envelop. This latter features adds very materially to the buoyancy or weight-sustaining capacity of the mattress-float. I prefer to construct the water-proof envelop of a cloth or fabric illustrated in Fig. 5, in which the two layers of strong, light cloth 4^a, 4^b inclose and are cemented together by a layer or film of water-proof paint 6. This multi-ply fabric is very serviceable and is especially adapted for the purposes of this invention because the water-proof layer or film is thoroughly protected from abrasion or wear by the outer cloth layers.

All of the seams of the water-proof envelop are made water-proof. I have illustrated in Fig. 7, one method of constructing the water-proof seam or joint. After the meeting edges of the envelop are sewed together, as at 7, the projecting ends of the cloth are turned back or returned as shown on the right-hand side of Fig. 7, and then fastened down by means of water-proof glue as shown on the left-hand side. The entire seam is then covered by a strip of cloth 8 which is securely fastened down across the entire seam and projecting ends by means of water-proof glue. This glued joint is preferably made upon the inside of the water-proof casing upon

three sides thereof to better protect it but must necessarily be placed upon the outside of the fourth side or end after the mattress has been inserted.

5 An outer cover or casing 10, which may be made of ticking, is placed over the inner water-proof envelop or casing. The marginal stiffening frame is constructed of hollow metal pipe or other suitable material, 12, 10 and is preferably secured within the outer sheath or cover. A narrow strip 14, may be sewed around the sides and ends of the outer cover, upon the inner side thereof and near the lower corner in the manner illustrated in Fig. 6, and after the frame is inserted, the free edge of the strip may be sewed down to the bottom of the cover to thereby incase the frame securely in a pocket. This forms a very secure union between the frame and the outer cover at the lower outer edge or margin of the cover so that the same may be maintained taut and will be prevented from sagging when sustaining the weight of the mattress and the 25 person or persons thereon. This is important as it is very desirable to prevent the mattress from becoming dished to let water into or upon the float.

For the purpose of providing suitable 30 fastening devices to secure persons or articles to the mattress-float or raft, lashings 15 are secured to the corners, preferably by passing through the outer covering 10 and being tied to the tubular frame 12. These 35 may conveniently be crossed diagonally over the top of the mattress. Suitable hand-holders or loops 16, are provided upon either side, and cross-straps 18, extend across the top and over the sides to furnish additional securing or holding devices. In 40 storm or on rough water, one is subjected to forward, backward and sidewise motions and in fact combinations of these which render it exceedingly important to provide 45 for properly securing oneself to the raft. It will be observed that the diagonal lashings 15, secured to the corners of the mattress-frame provide means for bracing against forward and backward motions, 50 while the cross-straps 18, take care of the sidewise or transverse movements and the two sets of securing-devices therefore co-operate in a proper manner to resist stresses in all directions. Thus a person may sit in 55 the triangular space between the intersection of the lashings 15 and the adjacent cross-strap 18, and by wrapping the lashings about the legs and grasping the cross-strap, be enabled to maintain a secure position 60 upon the mattress-float or raft. The pull upon either of the diagonal lashings is transmitted to the corner of the metal frame and is thus divided between and resisted by the two frame bars at right-angles to each 65 other, that is the thrust upon the frame is

divided into two component forces along the two frame bars. This arrangement subjects the frame to less racking than would be the case if the lashings extended longitudinally from end to end of the frame and 70 fastened to intermediate points in the bars, since such an arrangement would subject the bars to sidewise or transverse stresses tending to bend them. For the purpose of steadyng the raft I may attach a weight by 75 means of ropes secured to the corners of the frame so that the weight will be suspended centrally and act as an equilibrator. When the mattress is in use upon a bed, the ropes will extend along the edges and will 80 not be in the way or interfere in any manner with its normal use.

The many advantageous features of my invention will now be appreciated, especially by naval engineers. The water-tight inner envelop surrounding the mattress, provides a pneumatic floating body which is capable of sustaining heavy loads and possesses the advantage of remaining high or mostly above the water. The outer cover prevents abrasion and wear of the inner water-proof cover. The mattress itself is buoyant and furnishes a reserve of floating material which will keep the mattress and its load afloat even when the coverings become punctured or ruptured, although not as high above the water. The intersecting lashings and cross-straps, afford ample securing devices and transmit the stresses to the frame in the most advantageous manner.

It is often desirable to unite or superimpose two mattresses to form a duplex float. In this case it is preferable to arrange the frames at the top and at the bottom so as to more efficiently brace and stiffen the structure.

While I have described the structure illustrated in the drawings, in detail, I am aware that changes may be made therein without departing from the spirit of my invention.

I claim:—

1. A life-saving appliance, comprising a buoyant, resilient body portion, a water-proof envelop therefor, constituting a pneumatic bag or casing, an outer protective cover for said envelop, and a metal stiffening frame secured within the outer cover along the bottom edge thereof, and holding the same taut across the entire bottom of the body portion.

2. A life-saving appliance, comprising a buoyant, resilient body portion, a water-proof envelop therefor, an outer protective cover therefor, a metal stiffening frame secured to the outer cover along the bottom edge thereof, and holding the same taut across the entire bottom of the body portion, lashings secured to the corners of said frame, and cross-straps secured to inter- 130

mediate opposite points of the frame and intersecting said lashings, whereby strains on the lash are transmitted to the frame at the intersections of the side and end members thereof, said lashings forming longitudinal bracing members while said cross straps constitute transverse bracing members.

3. A life-saving appliance, comprising a buoyant, resilient, body portion having an inclosing cover or casing, an outer protective envelop therefor, having a pocket extending around the lower edge thereof, having its edges secured to the sides and bottom respectively of the envelop, and a stiffening frame secured within said pocket and holding said envelop taut across the bottom thereof.

4. A life-saving appliance, comprising a buoyant, resilient body portion, a water-

proof fabric surrounding the same and having the seams or joints sealed to provide a pneumatic casing, an outer protective cover, and a marginal stiffening frame within said cover and secured along the bottom edges thereof.

5. A life-saving mattress, comprising a buoyant resilient filling of material not readily absorbent of water, and having a suitable cover, an outer protective envelop therefor, and a rigid marginal reinforcing frame extending around the bottom edge of said mattress and secured within said outer protective envelop.

In testimony whereof I affix my signature in presence of two witnesses.

SAMUEL P. EDMONDS.
